V. C. DICKSON

ATHLETIC SHOE

Filed Dec. 27, 1923

Patented Aug. 17, 1926.

1,596,600

UNITED STATES PATENT OFFICE.

VIRGIL C. DICKSON, OF OWASSO, OKLAHOMA.

ATHLETIC SHOE.

Application filed December 27, 1923. Serial No. 683,038.

This invention relates to shoes and particularly to those shoes worn by athletes.

Great difficulty has been experienced, in the past, in securing cleats, to athletic shoes, which would stand the hard usage required of them under varied weather conditions without breaking loose from the shoe and while still retaining the shoe's flexibility.

The primary purpose of the present invention is the provision of an improved athletic shoe, the cleats of which will not become loosened under the varied wet and dry conditions and which will retain the shape and resiliency of its sole.

Another object of my invention is the provision of an athletic shoe having a cleat-carrying resilient inter or intra sole and an outer sole having openings for the cleats to protrude therethrough.

Another and further object of my invention is the provision of a shoe having an inter sole, and cleats integral therewith extending through the outer sole and having means attached to the respective cleats for holding the edges of the openings in place.

Referring to the drawing wherein I have illustrated an embodiment of my invention,

Fig. 1 illustrates a cross section of my invention on the line 1—1 of Fig. 2, but showing a part of the upper, in elevation,

Fig. 2 is a bottom plan view of the completed shoe, showing one of the cleats in cross section,

Fig. 3 is a bottom plan view of the shoe with the inter sole in position and before the outer sole is in place.

Fig. 4 is a fragmental cross-sectional view on the line 4—4 of Fig. 2.

Fig. 5 is a side elevation of the inter sole which carries the cleats and

Fig. 6 is a plan view of the outer sole showing the openings through which the cleats pass when the outer sole is applied.

Throughout the several figures, the same reference characters refer to the same or similar parts.

10 designates the upper of the shoe constructed according to my invention. The upper part of the shoe inner sole and welt portion are constructed in a well known manner the details of which form no part of the present invention.

Below the inner sole and welt 11, is an inter sole 12 which is preferably constructed of resilient metal having weakened portions as by cutting out portions 13 and 14, thus

leaving narrow strips 15, 16 in the middle portion or shank of the shoe, and narrow strips 17, 18 near the toe to permit the latter to bend during use. This inter sole portion preferably extends substantially the whole length of the shoe although this is not necessary.

Attached to the inter sole are cleat bodies which are rigid and preferably made integral therewith by welding or in any suitable manner. These cleat bodies are indicated at 19 on the heel portion of the inter sole and at 20 on the forward portion.

The inter sole 12 is attached to the inner sole by means of rivets 21, six in number being shown, two at the heel end, two at the toe and two under the ball of the foot. The rivet is placed with its head against the inter sole and a washer 22 through which the rivet stem is placed, is located within the shoe. After the rivets are in place, their ends are upset to hold the inter sole in place.

The outer contour of the inter sole is slightly smaller than the inner sole for a purpose to be described. The inter sole is provided with narrow slots 23, 24 adjacent the toe, slots 25, 26 adjacent the outer edges at the ball of the shoe and slots 27, 28 adjacent the heel for a purpose to be later set forth.

An outer sole 30 shown in Fig. 6 is made of the same size and shape as the inner sole 11. This outer sole is provided with openings 19^a, 20^a of the same size and shape as the cross-section of the cleat bodies at the points where they are joined to the inter sole. These openings are positioned so that they will register with the corresponding cleat bodies when the outer sole is applied. A suitable material for the outer sole has been found to be rubber or a substitute therefor.

After the outer sole is in place, the inner, inter and outer soles are secured together by stitching a line of stitching around the shoe adjacent the edge thereof in the usual manner as shown at 31. In addition to this, lines of stitching 32, 33, are run just inside the edges of the openings 13 and 14 after which the corners are connected with additional lines of stitching as shown in Fig. 2 at 34, 35. The openings 23, 24, 25, 26, 27, 28 in the inter sole are utilized to pass the stitching through to join the inner and outer soles together. Before the outer sole is applied, it may be, if desired, coated with a

suitable water proof cement as is well known in the art of shoe making.

After the outer sole is in place, the cleat bodies are provided with wearing portions which serve to hold the outer sole, adjacent the cleat bodies, in place and at the same time provide ground contacting surfaces which are of a yielding nature and may be replaced when worn or broken.

10 In the embodiment illustrated, I prefer to make the wearing portions of three parts. A collar 40 of hard wood, or other suitable material, is provided as shown in Fig. 4. This collar 40 has an opening centrally located to receive the cleat body 19 or 20 as the case may be. Holes are drilled through the collar portion and cleat body portion to provide for riveting the former to the latter, counter sunk holes being provided for the rivet heads. Before the collar portions are applied to the body portions of the cleat body, a suitable water proof cement is preferably applied to seal the joint between the cleat body and the collar.

25 The collar 40 does not cover the lower end of the cleat body. A suitable thimble having a hollowed-out portion, to receive the end of the cleat body, is provided. This thimble may be, as shown, constructed of 30 two complementary portions 41, 41^a which go on opposite sides and are riveted in place in a manner described for the collar 40. Similarly as in the case of the collars, a suitable water proof cement may be applied 35 to the inside portions of the thimble to seal the joints against the entry of moisture.

In use, a shoe constructed according to my invention, provides a maximum amount of comfort. The encounter of a cleat with 40 a stone or other hard substance does not bring a pressure on only one part of the foot, the strains being distributed by reason of the rigid connection of the cleat body to the inter sole. On the other hand, because of the flexible construction of the inter sole, the freedom of action of the foot is maintained.

After hard usage, the thimbles 41, 41^a, collars 40, outer soles 30 or inter soles 12 50 may be replaced as may be necessary.

While I have illustrated and described in detail an embodiment of my invention, I desire to have it understood that the showing is merely illustrative and that modifications 55 and changes may be made without departing from the spirit of my invention and within the scope of the appended claims.

Having described my invention what I claim and desire to secure by Letters Patent is:—

1. An athletic shoe having an upper portion and a sole portion, the sole portion comprising an outer sole, an inner sole and an inter metallic sole, and cleats having body 65 portions integral with the inter sole and

extending through the outer sole, and having ground engaging portions enveloping the portions of the cleats below the outer sole and also having means for non-rotatably securing the body portions and their respective ground engaging portions together. 70

2. An athletic shoe having an upper portion and a sole portion, the sole portion comprising an outer sole, an inner sole and an inter metallic sole, and cleats having body 75 portions integral with the inter sole and extending through the outer sole, and having ground engaging portions enveloping the portions of the cleats below the outer sole and also having rivet means extending through the body portions and ground engaging portions to hold the latter in place.

3. An athletic shoe having an inner sole, an outer sole, an inter sole extending over the shank of the shoe and between the outer and inner soles and having a cut out weakened portion adjacent the shank to provide flexibility, cleats having portions rigidly attached to the inter sole and having ground engaging portions below the surface 80 of the outer sole and having means passing through the weakened portion for securing the outer, inner and inter soles together. 85

4. An athletic shoe having an inner sole, an outer sole, an inter sole between the outer and inner soles and having a weakened portion adjacent the shank and another weakened portion between the ball of the shoe and the toe, said weakened portions 90 providing flexibility, cleats having portions rigidly attached to the inter sole and having ground engaging portions below the surface of the outer sole. 95

5. An athletic shoe having an upper portion and a sole portion, the sole portion 105 comprising a resilient metallic strip extending from the heel portion over the shank to the toe portion of the shoe, the strip having cleat body portions integrally attached thereto and extending therefrom and a 110 weakened portion intermediate the ends and permitting bending of the shoe when in use.

6. An athletic shoe having an inner sole, an outer sole, an inter sole between the outer and inner soles, cleats having portions 115 rigidly attached to the inter sole and extending through and beyond the outer sole and including means engaging the portion extending through the outer sole and bearing against the latter to hold it in place. 120

7. An athletic shoe having an inner sole, an outer sole, an inter sole between the outer and inner soles, cleats having portions integrally attached to the inter sole and extending through the outer sole and having wearing portions attached to and covering the portion extending through the outer sole. 125

8. An athletic shoe having an inner sole, an outer sole, an inter sole between the out- 130

er and inner soles and having cleat body portions rigid therewith and having a cut away portion through the body of the inter sole adjacent the shank of the shoe to form 5 an opening, and means passing through said opening, to secure the outer sole to the inner sole.

9. An athletic shoe having an inner sole, an outer sole, an inter sole between the outer 10 and inner soles and having cleat body portions rigid therewith and having a cut away portion through its body portion adjacent the shank of the shoe and stitching passing through the outer and inner soles 15 and the opening in the inter-sole to hold the outer, inter and inner soles together.

10. An athletic shoe having an inner sole, an outer sole, an inter sole between the outer 20 and inner soles and having cleat body portions rigid therewith, the inter sole being provided with perforations at intervals 25

and stitching passing through the inner and outer soles and through the perforations in the inter sole to hold the inter sole, the outer sole and the inner sole in relation 25 with each other.

11. An athletic shoe having an inner sole, an outer sole, an inter sole between the outer and inner soles, cleats having cleat body 30 portions rigidly attached to the inter sole and extending through the outer sole and having wearing portions attached to and covering the portion extending through the outer sole, the covering wearing portions comprising wooden bodies and securing 35 means above their bottoms and extending transversely into said cleat bodies of the cleats.

In testimony whereof I affix my signature.

VIRGIL C. DICKSON.
